UNITED STATES PATENT OFFICE.

EDWARD S. SAVAGE, OF ROCHESTER, NEW YORK.

FIGURE TOY.

Application filed March 16, 1925. Serial No. 15,751.

The present invention relates to figure toys and an object of the invention is to provide an improved mounting for the head of a figure toy by which the head will move forwardly and backwardly as the toy advances in order to simulate the movement of the head of an animal, bird or the like during walking. A further object of the invention is to provide front and rear supports for the figure toy which will have movement simulating a quadruped in walking. Still another object of the invention is to provide a construction in which the toy is pulled forwardly by a draft means connected to the lower portion of a pivotal front support for the body of the toy, and means is provided for operating the body so that it swings back and forth on the front support with reference to the draft means. A further object of the invention is to provide a figure toy having draft means, in which the body moves back and forth with reference to the draft means and is supported by two supports connected together in such a manner that the supports move in opposite directions as the body moves back and forth to simulate walking. Still another object of the invention is to provide a toy having a body supported by two supports, connected together, to move in opposite directions, one of said supports being weighted and having draft means connected thereto and provision being made for swinging the body back and forth with reference to the point of draft so that the toy simulates walking and, at the same time, the rear end of the body is adapted to swing upwardly under the inertia of the rear supports, in moving rearwardly to simulate kicking.

To these and other ends, the invention consists of certain parts and combinations of parts, all of which will be hereinafter described: the novel features being pointed out in the appended claims.

In the drawings:

Fig. 1 is a vertical section through the figure toy constructed in accordance with this invention;

Fig. 2 is a vertical section of the toy in a different position from that illustrated in Fig. 1;

Fig. 3 is a front view of the toy; and

Fig. 4 is a sectional view of another embodiment of the invention.

Referring first to the embodiment illus-

trated in Figs. 1 to 3 inclusive, 1 indicates the body of the toy and 2 the head. The head is supported, in this instance, on the body by two supporting links 3 and 4. The link 3 is pivoted at 5 in a recess 6 at the forward end of the body and at 7 in the recess 8 at the underside of the head. This link 3 simulates the neck of the animal and is grooved or pocketed in its rear surface at 9 to conceal the link 4, which is pivoted at 10 within the forward portion of the body and at 11 within the pocket 8 of the head 2. The links swing, in this instance, in parallel relation and, as a consequence, the head can move backward and forward relatively to the body, while always maintaining a substantially horizontal position, although moving in an arc.

The body, in this instance, is arranged on two supports, a front support and a rear support. The front support embodies two links 12, pivoted on a common axis 5 which is also the axis of the swinging of the link 3. These links 12 simulate the front legs of the animal and are connected, in this instance, at their lower ends by a shaft 13 which has traction wheels 14 rigidly secured thereto to turn therewith, the shaft turning in the links 12. The rear support comprises two links 15, pivotally connected at 16 to the body, and having their lower ends connected by a shaft 17 which turns in the links and has wheels 18 turning thereon.

In order that the front support may move rearwardly as the rear support moves forwardly or vice versa, a connecting means is employed between these two supports which, in this instance, comprises a link 19 pivoted to the rear support preferably through the medium of a bar 20 which extends through slots 21 in the body and connects the two links 15 at points eccentric to their turning axis 16. This link 19 is also pivotally connected to the front support on a bar 22 which operates through slots 23 in the body to connect with the links 12. The bar 20, which connects the link 19 with the rear support, is above the pivotal axis 16, whereas the bar 22 which connects the link 19 with the front support is below the pivotal axis 5. In this way the two supports are caused to move in opposite directions.

The bar 20 is also utilized as a pivot for the link 24 arranged within the body 1 and pivotally connected at 25 to the link 4 of the

head supporting means. It is thus apparent that the movement of the head is effected through the movement of the supporting means of the toy.

5 The mechanism for effecting the movement of the supports, in this instance, comprises a crank portion 26 on the shaft 13 connected by a link 27 pivoted to said crank portion and to a fixed point or pivot 10. A draft 10 means 28 is connected by a yoke 29 to the lower portions of the two links 12.

With this arrangement as the toy is pulled forwardly through the pull or draft cord, the traction wheels 14 are turned and in 15 turning turn the crank 26, which acting on the link 27, whose pivot is different from the pivot 5 of the front support, causes the front support to swing back and forth, shifting the body back and forth, and this swinging motion is transmitted by the link 19 to the rear support, causing the latter to swing in the direction opposite that from which the front support swings. Motion from the rear support is transmitted through the link 24 to 20 the links supporting the head 2. The front traction wheels are weighted as, for instance, being made of heavier material than the rear wheels. As a consequence when the toy is pulled, not only do the front legs and rear 25 legs move in the opposite direction, but due to the inertia of the rear support, the tendency is to lift the body 1, with the result that the toy simulates a kicking movement, the rear legs moving off the floor and the rear 30 end of the body elevating during the rear movement of the legs 15.

In the embodiment shown in Fig. 4, the body 1^a simulates a bird with a head 2^a supported by a front neck link 3^a pivoted at 5^a 40 to the body and at 7^a to the head. This neck link is grooved like the embodiment shown in Fig. 1 to house or conceal a link 4^a pivoted at 10^a to the body and at 11^a to the head. An extension 4^b on the link 4^a connects with 45 a link 27^a with a crank 26^a on the shaft 13^a on the front support 14^a. It is apparent that in this embodiment the turning or movement of the front supporting wheels 14^a transmits through the link 27^a motion to the link 4^a 50 and consequently to the head, so that as the body moves forward, the head 2^a moves back and forth.

From the foregoing it will be seen that there has been provided in figure toys, a 55 means for mounting a head so that it moves back and forth while remaining in a substantially horizontal position under the action of the movable support for the body of the toy. In one form, the movable support 60 is a swinging member, whereas in the other the movable support makes a complete rotation, in both traction operated means effects the movement of the head. A novel means is employed for connecting a front support 65 and a rear support for a figure toy, so that

as the front support is pulled forwardly, the body moves back and forth and these supports move in opposite directions to simulate walking. A novel means is also employed for causing the rear supports to simulate a 70 kicking movement on their rearward movements, the rear end of the body at the same time being elevated at its rear end.

What I claim as my invention and desire to secure by Letters Patent is:

75 1. A figure toy comprising a movable body, a head, two supporting links for the head, each pivoted to the head and to the body, one in rear of the other, one of said supporting links serving as the neck of the figure, and means for moving said links to effect the movement of the head relatively to the body, said means being controlled by the movement of the body.

2. A figure toy comprising a body, a head, 80 two supporting links for the head, each pivoted to the head and to the body, one in rear of the other, one of said links having a recess in which the other is concealed.

3. A figure toy comprising a movable 85 body, a head, two supporting links for the head, each pivoted to the head and to the body, one in rear of the other, one of said supporting links acting as the neck of the figure, and traction operated means connected with the links for moving the head and body relatively.

4. A figure toy comprising a body, two pivoted supports for the body, means connecting said supports to cause them to move 100 in opposite directions, traction means on one of the supports and eccentric connection between the traction means and the body to effect the movement of the supports.

105 5. A figure toy comprising a body, two pivoted supports for the body, means connecting the supports to cause them to move in opposite directions, traction means movable on one of the supports and eccentric 110 connection between the traction means and the body to one side of the support on which it is mounted for effecting the movement of both supports.

6. A figure toy comprising a body, two 115 pivoted supports for the body, a link pivotally connecting said supports to cause them to move in opposite directions, traction means mounted on one of said supports an eccentric connection between the traction means and the body at one side of the pivot of the support to effect the movement between such support and the body, and through the link between the supports.

120 7. A figure toy comprising a body, two 125 pivoted supports for the body, means connecting the supports to cause them to move in opposite directions, means for weighting the forward support for causing the front end of the body to be heavier than the rear 130

end, draft means connected to the lower portion of the front support, traction means and an eccentric connection between the traction means and the body to cause a movement between said forward support and the body and consequently a movement of the rear support, so that the inertia of the rear support will effect the movement of the rear end of the body upwardly as the rear support moves rearwardly.

8. A figure toy comprising a body, two pivotally mounted supports, means connecting the supports to cause them to move in opposite directions, traction means on the forward support and an eccentric connection between the traction means and the body to one side of the pivot of the forward support to effect the relative movement between the body and the forward support, and draft means connected to the lower portion of the forward support, so that as the forward support is pulled forwardly, the traction means will effect a relative movement between the forward support and the body and the rear support will be operated through its connection with the forward support.

9. A figure toy comprising a body, front and rear supports pivoted to the body, means connecting the front and rear supports to cause them to move in opposite directions, draft means connected to the lower portion of the front support, traction means for the toy, and an eccentric connection between the body and the traction means for effecting the relative movement between the supports and the body.

10. A figure toy comprising a body, front and rear supports pivoted to the body, means connecting the front and rear supports to cause them to move in opposite directions, draft means connected to the lower portion of the front support, traction means for the toy and an eccentric connection between the body and the traction means for effecting the relative movement between the supports and the body, the front support being weighted so that as the movement between the supports for the body takes place, the inertia of the rear support will tend to swing upwardly the rear end of the body.

11. A figure toy comprising a body, a support pivoted to the body, a traction wheel mounted to turn on the support below the pivot of the body and parallel with the axis of swinging of the body, said support being mounted to swing about the axis of turning of the traction wheel, draft means flexibly connected to the lower part of the support adjacent the pivotal connection of the latter with the traction wheel, and a link pivotally connected to the body in rear of the pivotal connection of the support, said link being eccentrically connected

to the traction wheel so that as the traction wheel is pulled along the body moves back and forth on the support.

12. A figure toy comprising a body, two pivotally supports for the body, a link pivotally connecting said supports so that they move in opposite directions, traction means on one of the supports and an eccentric connection between the traction means and the body to one side of the pivot of the support on the body for moving said supports.

13. A figure toy comprising a body, two pivotally mounted supports, means for connecting the supports to cause them to move in opposite directions, a link pivoted to the body in rear of the pivot of the front support, and a traction wheel mounted to turn on the front support and having eccentric connection with said link for effecting the longitudinal movement of the latter relatively to the front support.

14. A figure toy comprising a body, a pair of supports pivotally mounted on the body one in front of the other, the forward support having a traction wheel mounted to turn thereon, means connecting the supports to cause them to move in opposite directions, and a link pivotally connected to the body in rear of the forward support and having an eccentric connection with the wheel in rear of the forward support.

15. A figure toy comprising a body, a pair of supports pivotally mounted on the body, one in front of the other, the forward support having a traction wheel mounted to turn thereon, a link connecting the supports and pivoted above the axis of one and below the axis of the other so as to cause them to move in opposite directions, and a link pivoted to the body in rear of the front support and having an eccentric connection with the traction wheel of the front support.

16. A figure toy comprising a body, a head, two links pivotally connected to the head on separate axes out of line with each other and to the body on separate axes out of line with each other, a pivotal support for the body, and a link pivotally connected to one of the links and to the pivotal support to one side of the pivotal axis of the latter.

17. A figure toy comprising a body, a head, two links pivotally connected to the head on separate axes out of line with each other and to the body on separate axes out of line with each other, a pivotal support for the body, a link pivotally connected to one of the links and to the pivotal support to one side of the axis of the latter, a pivotal support for the body in front of the first mentioned support, and means for connecting the two supports to cause them to move in opposite directions.

18. A figure toy comprising a body, a

pair of supports pivotally mounted on the body, one in front of the other, traction wheels mounted to turn on the supports, a link pivotally connected to the body in rear of the forward support and having an eccentric connection with the forward traction wheel so that as the body moves forwardly on the two traction wheels, the body

swings on the forward support to elevate the rear support and its traction wheel and ¹⁰ permits the movement of the rear support relatively to the body, and draft means connected to the lower portion of the forward support.

EDWARD S. SAVAGE.
